UNITED STATES PATENT OFFICE.

SAMUEL D. HUNT, OF YOUNGSTOWN, OHIO.

TROLLEY.

No. 890,058.

Specification of Letters Patent.

Patented June 9, 1908.

Application filed October 9, 1907. Serial No. 396,569.

To all whom it may concern:

Be it known that I, SAMUEL D. HUNT, a citizen of the United States, residing at Youngstown, in the county of Mahoning and State of Ohio, have invented certain new and useful Improvements in Trolleys, of which the following is a specification.

This invention relates to an improvement in trolleys for electric railway systems, and 10 has particularly in view a practical construction of trolley head or harp comprising means for maintaining an effective contact with the feed wire or wires under all conditions, while at the same time guarding against the loss of 15 contact with the feed wire or wires at curves and such other points where trolleys are generally liable to leave the wire. In this connection, the invention provides a construction possessing special utility with main and 20 auxiliary feed wires located at curves and other points to be specially guarded, and also beneath bridges and viaducts where the main feed wire is brought particularly low.

With these and other objects in view 25 which will be readily apparent to those familiar with the art, the invention consists in the novel construction, combination and arrangement of parts hereinafter more fully described, illustrated and claimed.

30 In the accompanying drawings, exemplifying the preferred arrangement of parts; Figure 1 is a side elevation of one form of trolley embodying the present invention and showing the general relation of parts to each 35 other and to the main feed wire or conductor. Fig. 2 is a front view of the trolley head or harp illustrated in Fig. 1 and showing the operative relation thereof to main and auxiliary feed wires at curves or other places. 40 Fig. 3 is a side elevation of a practical form of the invention embodying a conventional type of trolley wheel for engagement with the main feed wire. Fig. 4 is a front view of the form of the invention shown in Fig. 3, 45 and illustrating the relation of parts in connection with the main and auxiliary feed wires at curves or other places.

Like references designate corresponding parts in the several figures of the drawings.

50 The present invention contemplates associating with the trolley pole 1 for an electric motor car, a novel and practical form of trolley head or harp designed to be carried at the upper or outer end of the pole. This 55 particular head or harp may be constructed in various ways, and in connection with dif-

ferent kinds of trolley elements for engagement with the feed wires, but in order to exemplify the scope of the invention in this connection, a special form of construction 60 that may be resorted to is suggested in Figs. 1 and 2 of the drawings. Referring to said Figs. 1 and 2 of the drawings, the trolley head or harp illustrated therein is shown as comprising in its organization a pair of upright rotatable trolley spools 3 journaled on the fixed 65 upright supporting journals 4 suitably fitted to the upper or outer end of said pole 1. These spools are preferably duplicates in construction and each consists of an elongated body of a well defined dumb bell shape, and therefore embodying in its make up an intermediate longitudinally concaved or dished cylindrical bearing waist 5, and a pair of terminal contact heads 6 and 7 arranged 70 respectively at opposite ends of the waist portion 5. The said heads 6 and 7 of the individual trolley spools are of a spherical or spheroidal design, and therefore have a uniform ball-like rolling contact with the feed 75 wires engaged thereby, while the round longitudinally concaved waists 5 of the spools likewise have an easy rolling contact with the feed wires when, under some conditions, they are brought into contact therewith. 80 Preferably the opposite spools 3, and their supporting journals 4 are set in upwardly divergent relation, though in the embodiment of the invention shown in the drawing this 85 relation may very nearly approach the parallel, or in fact be entirely or truly parallel, without departing from the scope thereof. However, in addition to the above referred 90 to relation of the spools to each other the same are usually both arranged at an inclination of about ten degrees from the perpendicular to secure the best results, though it will be understood that the angularity of the 95 spools with respect to each other, and also in relation to the pole may be varied.

100 The spools may be held upon their supporting journals or spindles 4 by any suitable retaining means such as the nut retainer 8 shown in Fig. 2 of the drawings, and also preferably have a bearing at their lower ends in suitable bearing seats 8^a provided in a bearing plate 8^b which may be suitably placed on the end of the trolley pole. These structural details however may be varied to suit any particular condition under which 110 the spools may be employed. The main feed wire or conductor 9 is illustrated in the

drawings as being suspended from a centrally arranged hanger arm 12 carried by an arched hanger bracket 13, which bracket may also be conveniently provided at opposite sides of the support for the wire 9 with the oppositely located pendent bracket arms 14 and 15 to which are respectively attached the auxiliary wires 10 and 11. These latter wires are shown as being located a material distance below the plane of the wire 9, and are designed to be strung for service, in connection with the main feed wire, at curves or other locations where it is desirable to guard against loss of contact between the trolley and the conductor or conductors.

A distinctive feature of the present invention is that of the provision of a secure and effective coöperation between the trolley head or harp and the auxiliary wires 10 and 11 wherever these wires occur in the system. To provide for this the invention contemplates combining with the trolley spools the additional feature of providing the trolley head or harp with a pair of oppositely arranged supplemental trolley wheels 16 and 17 journaled on suitable axles 18, and respectively engaging and rolling upon the said auxiliary wires 10 and 11, as may be plainly seen from Fig. 2 of the drawings.

Under normal conditions, the lower contact heads 7 of both spools 3 will have an easy rolling contact under and against the main feed wire 9, but in the event of there being any tendency of the trolley to "jump" away from the main feed wire (at points where the auxiliary wires are not located) this would be effectually checked by the upper contact heads 6 coming into engagement with the main feed wire or conductor. Also, in cases where the trolley is brought especially low, as for instance beneath bridges and viaducts, the said upper contact heads 6 will be tilted against the feed wire or conductor, and thus safeguard the trolley against loss of contact. Furthermore lateral thrust or side movement of the trolley is taken care of, without loss of contact, by the rounded waists 5 of the spools.

As already explained, the foregoing description details a special form of trolley

harp construction that may be resorted to in carrying out the invention, but it will be understood that instead of the specially shaped trolley spools 3 referred to, any suitable or approved form of trolley element may be carried by the pole for engaging the main feed wire. Hence, the invention may be carried out in a very simple and practical manner by combining the supplemental trolley wheels 16 and 17 with a single trolley wheel 19 journaled in suitable bearings 20 carried at the outer or upper end of the pole, and contacting beneath the main feed wire 9 in a common and well known manner.

55

60

65

From the foregoing it is thought that the construction, operation and advantages of the invention will be readily apparent without further description.

I claim:—

1. In a trolley system, the combination with the main feed wire and auxiliary side wires, of a trolley head having a main trolley element engaging beneath the main feed wire, and a pair of separate supplemental trolley wheels arranged to engage the auxiliary wires at the upper side of the latter.

2. In a trolley system, the combination with a main feed wire and auxiliary wires, of a trolley head having spools for engagement with the main wire, and a pair of supplemental wheels for engagement with the auxiliary wires.

3. In a trolley system, the combination with a main feed wire and auxiliary side wires, of a trolley head having a pair of upright rotatable spools, and a pair of oppositely located supplemental trolley wheels.

4. In a trolley system, the combination with a main feed wire and auxiliary wires arranged below the latter, of a trolley head having a pair of upright rotatable spools, and below the plane of the latter also having a pair of oppositely located supplemental trolley wheels.

In testimony whereof I hereunto affix my signature in the presence of two witnesses.

SAMUEL D. HUNT.
